UNITED STATES PATENT OFFICE.

HERMAN M. BIR, OF LIMA, OHIO.

MEANS FOR DIFFUSING AND COLORING RAYS OF LIGHT.

Application filed September 1, 1922. Serial No. 585,720.

This invention relates to new and useful improvements in means for coloring and diffusing rays of light, the primary object of the invention being to provide an unbreakable body adapted to be positioned to intersect rays of light for diffusing or coloring the same thereby providing means whereby strong and durable illuminated signs may be manufactured as well as hoods for incandescent electric light bulbs when it is desired to cast different colored rays from the bulb.

Another important object of the invention resides in the provision of a body of the above character which is flexible so as to be capable of being formed into various shaped objects such as the hoods used on electric light bulbs for changing the color thereof; the flexibility of the body without detrimental effects thereto also adding an advantage to the device in that it is unbreakable, and thereby well adapted for use in connection with illuminated signs and the like.

A further object of the invention resides in the provision of means whereby an illuminated sign can be formed from a single sheet of material, thereby obviating the necessity of cutting out letters and placing transparent or translucent material back of the cut out letters so as to permit rays of light through the letters as is customary at the present time.

Other objects and advantages of the invention will become apparent during the course of the following description.

In the accompanying drawings forming a part of the description and wherein like numerals are employed to designate like parts throughout the several views,

40 Figure 1 is a perspective view of a flat piece of the material used in carrying the invention into practice.

Figure 2 is a perspective view of a piece of material provided with a letter in accordance with my invention.

Figure 3 is a vertical section through the same, and

50 Figure 4 is a perspective view of a hood for incandescent electric light bulbs constructed in accordance with the invention.

Fig. 5 is a plan view of a modified form of the invention.

In the accompanying drawings, wherein for the purpose of illustration are shown various embodiments of the invention, and which shows only a few applications of the

invention, the numeral 5 designates a flat sheet of material, preferably very thin metal, but not necessarily so, as the invention may be provided of other material such as fiber, insulating material, or any other kind of material which is thick enough to stand up alone. This piece of material is provided throughout with a plurality of holes or apertures 6 which may be arranged in rows or any other manner so that they are arranged in close proximity to one another to form the sheet of material into a foraminous body. Instead of forming a foraminous body in the manner herein devised it may be simply made up of a piece of wire mesh or any other kind of reticulated material.

In accordance with the invention, this foraminous material is coated on one or both sides with enamel, paint, porcelain, glass or vitrifiable colors or the like and the holes or perforations are either left open or they may be closed with a transparent or translucent medium such as glass, varnish, oil which will harden or other mediums, just so light may pass through the openings or apertures. The material thus provided can then be cut to form various letters, or the material before being coated and the apertures therein filled, can be first cut into the shape of the desired letters for the formation of a sign and then finished in the same manner as hereinbefore described. The letters can then be assembled in front of a source of light to provide the desired advertising sign, and when the light is strong enough the rays of light passing through the openings or apertures 6 and the material filling the same are caused to diffuse, thereby rendering the letters quite visible.

95 In Fig. 2 I have shown a different way of providing a sign under the present invention. In this instance, an imperforate sheet of material 7 large enough to contain the sign is obtained, and the letters or data to appear thereon are outlined and within these outlines the material is provided with a plurality of perforations or holes arranged very close together to form the letter or data desired. The body or material 7 is then coated the same way as the piece of material 5 hereinbefore described, and the apertures or holes 8 are filled in the same manner as the holes 6 and with the same kind of material so that rays of light will pass through the letters to cause the same to be illuminated and clearly visible.

If desired, the letters or data may be embossed in the material, and the embossed portion 9 as shown in Fig. 3 is provided with holes or apertures 10 which are filled with the transparent or translucent material in the same manner as the preceding forms of invention.

In Fig. 4 I have disclosed another application of the invention and which is used for causing electric lights to shed different colored lights, or to remove the glare therefrom. This hood 11 for electric lights is made cup-shaped and is provided with apertures or holes which are filled with transparent or translucent material as in the preceding modifications. The edge of the cup-shaped hood 11 is provided with a bead 12 from which extend tabs or tongues 13 which are adapted to slip over the largest end of the electric light bulb and clasp against the sides thereof to retain the hood on the larger end of the bulb. These tongues 13 are preferably resilient and extend parallel with the sides of the hood 11 as shown so as to conform to the configuration of the ordinary electric light bulb.

This hood is then coated with enamel, paint, porcelain, glass or vitrifiable colors et cetera. The perforations or apertures may be left open or they may be closed by

the coating placed on the material, or with a transparent or translucent medium such as glass, varnish, oil and the like.

The foregoing description and accompanying drawings have reference to what might be considered the approved or preferred form of my invention. I desire it to be understood that I may make such changes in the construction, combination and arrangement of materials, dimensions, et cetera, as may prove expedient and fall within the scope of the appended claim.

Having thus fully described my invention what I claim is:

A sign comprising a flexible sheet of material adapted to be placed in front of a light, portions of said material being pressed out to form convexed bulged portions assuming the form of letters or symbols, said convexed portions being provided throughout with a plurality of apertures arranged in close proximity to one another, the material immediately adjacent the outline of said letters being imperforate to strengthen the apertured portion of the material, and material filling said apertures for diffusing the rays of light passing therethrough.

In testimony whereof I affix my signature.
HERMAN M. BIR.
